UNITED STATES PATENT OFFICE.

EDWIN V. BABBITT, OF FAIRHAVEN, MASSACHUSETTS.

TOY SOLDIER.

Application filed June 8, 1926. Serial No. 114,482.

This invention is embodied in a figure toy mounted on a platform, supported by running gear adapted to run on a floor, a standard fixed to and projecting upward from the platform, a military figure supported by the standard above the platform and including a body and oscillating legs depending therefrom, and means operable by an element of the running gear to oscillate the legs simultaneously in opposite directions, the object being to produce the effect of goose-step marching, and to provide a sheet metal standard which is adapted to firmly support the body without being objectionably conspicuous.

Of the accompanying drawings forming a part of this specification,—

Figure 1 is a side view of a figure toy embodying the invention.

Figure 2 is a front view of the same, the platform being shown in section on the line 2—2 of Figure 1.

Figure 3 shows in perspective and on a larger scale, the standard, a portion of the platform, and the means actuated by the running gear for oscillating the legs.

The same reference characters indicate the same parts in all of the figures.

In the drawings, 12 designates a platform, preferably of sheet metal, provided with a marginal flange 13. The platform is provided with running gear which includes axles 14 and 15, journaled in bearings in the flange 13, and traction wheels 16' on the axles. The traction wheels of the rear axle 14, which I call the operating axle, are fixed to said axle to rotate it. To the platform is fixed an upstanding standard, preferably composed of a single piece of pressed sheet metal and including a channeled portion 16, fixed at its lower end to the platform and provided with seats 17 at its upper end for a purpose hereinafter described, and a shank portion 18, projecting upward from the channeled portion.

The figure includes a body portion 19, bearing at its lower end on the seats 17, and at its back on the shank portion 18, the latter being attached to the body portion by fasteners, indicated at 20.

The figure also includes legs 21, pivoted at 22, to the lower end portion of the body, and adapted to oscillate in parallel planes.

I provide means actuated by the rotation of the operating axle 14, for oscillating the legs simultaneously in opposite directions,

and thereby producing the effect of goose-step marching.

In the preferred embodiment of the invention here shown, I organize said means as next described.

The axle 14 is provided with a crank 23, revolved by the rotation of the axle. The legs are provided with pivoted rearwardly projecting arms 24. A rocking compound crank-shaft is journaled in bearings 25 (Figure 3), in the flanges or wings of the channeled portion 16 of the standard. Said compound crank-shaft includes the alined portions 26, journaled in the bearings 25, a central crank 27, connected by a rod 28 with the axle crank 23, and two oppositely projecting end cranks 29, engaged with the leg arms 24.

The arrangement, clearly shown by the drawings, is such that when the axle 14 is rotated, the compound crank-shaft is rocked in its bearings 25, so that the legs 21 are oscillated simultaneously in opposite directions, to produce the effect of goose-step marching.

The channeled form of the standard portion 16 imparts suitable stiffness thereto, so that said portion, and its seats 17, firmly support the body 19, without being objectionably bulky and conspicuous.

The lower end of the standard is preferably provided with integral tongues 30, which are inserted in slots formed for their reception in the platform 12, and bent outward against the under surface of the platform, as shown by Figure 2, and by dotted lines in Figure 3.

The platform is provided with an opening 32 (Figure 3), permitting the revolution of the crank 23 and the necessary endwise movements of the rod 28.

I claim:

1. A toy soldier comprising a platform, running gears supporting the platform and including a crank axle and traction wheels fixed thereto, an upstanding support fixed to the platform, a soldier figure body fixed in upright position to said standard, two legs pivoted to the lower end of said body, each leg consisting of a rigid unjointed piece, a rock shaft oscillatively mounted in the standard, and having three cranks, separate connecting arms pivoted to two of said cranks and to the legs, respectively, and a connecting rod between the third rock shaft crank and the axle crank; said rock shaft being

oscillated by rotation of the axle and its channelled portion with body seats at the 10 leg-connected crank being disposed to swing upper end thereof and a shank portion rising the legs simultaneously in directions opposite to one another simulating the leg movements of a soldier in marching with the goose step.

2. In a figure toy, a base structure, a standard secured to and rising from said structure formed of pressed sheet metal having a

channelled portion with body seats at the 10 upper end thereof and a shank portion rising above said seats, and a figure body seated at its lower end on said seats and secured at its upper part to said shank.

In testimony whereof I have affixed my 15 signature.

EDWIN V. BABBITT.
